UNITED STATES PATENT OFFICE

GEORGE B. BOSCO, OF CHICAGO, ILLINOIS

FORM CLAMP

Application filed May 4, 1931. Serial No. 534,730.

My present invention relates to improvements in form clamps for use in connection with band iron for securing together opposite sides of forms or molds for casting concrete.

5 An article of the same class was disclosed in United States Letters Patent No. 1,475,424, issued to me November 7, 1923, and my experience with the article therein set forth and described disclosed certain conditions which 10 such structures should be designed to meet in order to permit of their most economical and extensive and dependable use. That is to say, as band iron has relatively little thickness to width the clamping of the band iron 15 should be, if possible, so as not to tend to shear or even score the same as the band iron, in event of a break, is sure to break at the partially sheared or scored place. Again, the clamp should be so designed as to permit of either side being applied to the form and to 20 co-operate with the pulling up or tightening tool on either side and in both directions as it not infrequently occurs that the pulling up tool may be easily worked in one direction 25 while there is no room whatsoever in the other direction for its attachment or operation.

Again, it is highly desirable that such clamps be provided with as large an opening 30 as possible for the passage of the band iron, both to permit of the use of different widths and thicknesses of band iron with the same clamp and also to permit of the easy threading on and removal of the band iron from the clamp as the band iron is not infrequently 35 bent before its association with the clamp and it is always bent after its association with the clamp. Such a clamp should be designed so it can be made as economically as possible 40 and at the same time should be stiff and sturdy throughout its entire length so as to permit of its use in spanning the distance between parallel battens or whalers, or other reinforcements for the sides of the forms. 45 It is also desirable with such structures to provide a sturdy clamping means which will not bend in use, and shall not be detachable from the clamp.

I have provided a structure which will satisfy 50 conform with the above conditions

which I have illustrated in the accompanying drawings, in which—

Fig. 1 is a perspective of my improved form clamp with the wedge removed.

Fig. 2 is a side elevation of my form clamp 55 partially broken away to show the relation of the wedge element therewith.

Fig. 3 is a longitudinal section on line 3—3 of Fig. 2 particularly showing the way in which the band iron is bent when the wedge 60 member is first driven in.

Fig. 4 is a view similar to Fig. 3 illustrating how the strain of the band iron after the wedge has been set tends to more firmly lock it in position.

Fig. 5 is a fragmental detail to an exaggerated scale for clearly illustrating the locking of the band iron upon the application of a force sufficient to displace the wedge from its original set; and

Fig. 6 is a section on line 6—6 of Fig. 2 showing a means for retaining the wedge member in assembly with the clamp.

Similar reference characters refer to similar parts in the respective views.

I have chosen a general I-beam pattern for my clamp as securing a maximum of strength with the amount of metal employed in its construction. This I-beam consists of the parallel flanges 10 and 11 connected by a central 80 web 12, and in the ends of the web 12 I have provided cut out portions or slots 13 to facilitate the nailing of the clamp in position on the forms. As the slots, hereinafter mentioned, for the passage of the band iron, are so large 85 it is possible to more easily and economically space and nail the clamps in position before the sides of the forms are put in position.

Centrally of the length of the clamp I provide a pair of spaced transverse webs 14 and 15, the central web 12 merging with the transverse web 14 is interrupted between the webs 14 and 15, and is continued from the transverse web 15 as parallel spaced webs 12a and 12b to adjacent the end of the clamp where 95 they again merge into the longitudinal central web 12 through transverse web 16 disposed obliquely to the transverse webs 14 and 15.

It is possible to cast this structure very 100

economically as but a single baked core is necessary in forming the slot bounded by the walls 12a, 12b, 14 and 16 and the opening between the transverse webs 14 and 15 may be provided with what are known as green cores. After the above described structure is cast it may be economically and very thoroughly processed to secure what is known as a malleable casting, as all of its parts are relatively thin so as to permit of thorough processing.

After the structure hereinbefore described has been cast and processed I insert in the slot bounded by the walls 12a, 12b, 14 and 16 a wedge or locking member 17 and secure it from removal by partially punching therefrom a piece of metal 18, as most clearly shown in Fig. 6. The side of the wedge or locking member 17 adjacent the wall 16 is given the same obliquity as that wall, while the side of the member 17 which is opposite the transverse web 14 is parallel therewith.

The channel or slot between the walls 14, 12a, 12b, and 16 is extended slightly into the transverse wall 14 so as to provide the shoulders 14a and 14b and the slot is so much oversize with respect to the thickness of the member 17 that it will seat the band iron 19 between the shoulders 14a and 14b without any tendency to shear or score the band iron. The edges of the member 17 are square with respect to the sides thereof and parallel with the faces of webs 14 and 16 so that after the band iron has been seated between the shoulders 14a and 14b any strain upon the band iron will tend to capsize the member 17 in its laterally oversized slot, thereby more firmly gripping the band iron. This action is indicated in Fig. 4 and in a more exaggerated way in Fig. 5.

It will be seen from the foregoing description, taken in connection with the drawings, the wedge or gripping member 17 need only be driven into the slot sufficiently to seat the band iron between the shoulders 14a and 14b.

It will also be seen that if through ignorance it is attempted to drive the wedge 17 into the slot further than is required, the relatively broad edges of the wedge will resist such action which, together with the laterally oversized slot, will prevent any shearing or scoring of the band iron.

The opening for the passage of the band iron between the transverse webs 14 and 15 and the flanges 10 and 11 may easily be made so large as not only to permit the easy threading of the band iron therethrough but also to permit of the use of a single size of clamp with all the thicknesses and widths of band iron now generally employed in building construction.

Probably the most important single aspect of my new clamp is the prevention of the shearing or scoring of the band iron as dangerous and expensive accidents may result from such shearing or scoring. It should

also be noted that strain upon the band iron operates to increase the grip of the clamp thereon. However, the great strength of the clamp, the possibility of using it over and over again indefinitely, and the convenience and economy of time in its use and its applicability to many situations in which my former clamp could not be used, are all important.

Having described my invention what I claim as new and desire to secure by Letters Patent is:

1. A form clamp comprising an elongated form of metal with opposite parallel faces, having extending between a pair of said parallel faces a longitudinally elongated, transverse channel with an oblique end wall and an opposite rectangular end wall, said form of metal also having a second transverse channel therethrough intersecting with said first mentioned channel adjacent one end wall, and a wedge co-operating with said first mentioned channel having squared edges parallel respectively with the oblique and rectangular ends of said channel, said wedge being of less thickness than the channel with which it co-operates, whereby it will bend, without shearing or scoring, band metal extending through said second transverse channel, and whereby a strain upon said band metal will tighten the grip of said clamp thereon.

2. A form clamp comprising parallel spaced plates, connected by an interrupted longitudinal web and a pair of spaced transverse webs, one end of said longitudinal web merging with one of said transverse webs and the other end of said longitudinal web being bifurcated and extending from the other of said transverse webs, which is centrally interrupted, into merger with an oblique transverse web from which extends the remainder of said longitudinal web, said spaced plates being perforate opposite the inner edges of said transverse and bifurcated longitudinal webs, and a wedge having squared edges co-operating with the channel between said transverse and bifurcated longitudinal webs of less thickness than the width of said channel whereby a displacement of one edge of said wedge will cause the same to bind in said channel.

GEORGE B. BOSCO.
